US00D811237S

(12) **United States Design Patent** (10) **Patent No.:** **US D811,237 S**
(45) **Date of Patent:** **** Feb. 27, 2018**

(54) **CLEANING IMPLEMENT**

(71) Applicant: **THE CLOROX COMPANY**, Oakland, CA (US)

(72) Inventors: **Kerry D. Azelton**, Pleasanton, CA (US); **John D. English**, Pleasanton, CA (US)

(73) Assignee: **The Clorox Company**, Oakland, CA (US)

(**) Term: **15 Years**

(21) Appl. No.: **29/564,853**

(22) Filed: **May 16, 2016**

(51) LOC (11) Cl. **09-01**

(52) U.S. Cl. **D9/686**; D32/35

(57) **CLAIM**

The ornamental design for a cleaning implement, as shown and described.

DESCRIPTION

FIG. 1 is a front perspective view of a cleaning implement and showing our new design;

FIG. 2 is a cross-section view taken along line 2-2, in FIG. 1

FIG. 3 is a rear perspective view;

FIG. 4 is a cross-section view taken along line 4-4, in FIG. 3

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a rear view thereof.

(Continued)

The broken lines shown on the drawings are showing portions of the cleaning implement that form no part of the claimed design.

1 Claim, 7 Drawing Sheets
